VENDING MACHINE

Carl W. Sunberg, Bloomfield Hills, Mich., William Schwartz, Needham, Mass., and Albinus G. Bodoh, Prospect Heights, Ill., assignors to The Seeburg Corporation, Chicago, Ill.

Filed Aug. 25, 1964, Ser. No. 81,435

Term of patent 14 years

(Cl. D52—3)

FIGURE 1 is a front perspective view of a vending machine showing our new design;

FIGURE 2 is a front elevational view thereof;

FIGURE 3 is a left side elevational view thereof, the right side elevational view being substantially a mirror image thereof; and

FIGURE 4 is a sectional view taken along line 4—4 in FIGURE 2.

The rear, top, and bottom of the vending machine are plain and unornamented.

The dominant features of our design reside in the portions shown in full lines.

We claim:

The ornamental design for a vending machine, substantially as shown and described.
